HANGAR FOR HIGH WING AIRCRAFT

Homer F. Kliewer, deceased, late of Orosi, Calif., by Betty J. Kliewer, administratrix, Orosi, Calif., and John E. Rawson, Dinuba, Calif., assignors of two-sixths to Elmer H. Schuil, Dinuba, Calif.

Filed Sept. 18, 1968, Ser. No. 13,578

Term of patent 14 years

Int. Cl. D25—04

U.S. Cl. D13—1

FIG. 1.

FIG. 2.

FIG. 3.

FIG. 4.

FIG. 5.

FIG. 1 is a perspective view of a hangar for high wing aircraft showing our new design.

FIG. 2 is a top plan view thereof.

FIG. 3 is an elevational view of one side thereof, the other side being of the same ornamental appearance.

FIG. 4 is an elevational view of one end thereof, the other end being of the same ornamental appearance.

FIG. 5 is a bottom plan view thereof.

We claim:

The ornamental design for a hangar for high wing aircraft, as shown and described.
